(57) **CLAIM**

I claim the ornamental design for a magnifier, as shown and described.

DESCRIPTION

FIG. 1 is a top plan view of a magnifier;

FIG. 2 is a bottom plan view of the magnifier of FIG. 1;
FIG. 3 is a right side plan view of the magnifier of FIG. 1,
the left side plan view being a mirror image thereof; and,
FIG. 4 is a top perspective view of the magnifier of FIG. 1.
The broken lines illustrate portions of the magnifier that
form no part of the claimed design.
